United States Patent Office

Des. 188,585

Patented Aug. 9, 1960

188,585

FLOCKED TEXTILE FABRIC

Natalie Leavy, Clifton, N.J., assignor to Decorative Fabrics Company Incorporated, Pawtucket, R.I., a corporation of Rhode Island

Filed Feb. 9, 1960, Ser. No. 59,321

Term of patent 14 years

(Cl. D92—1)

The figure is a plan view of a flocked textile fabric, showing my new design.

A full width is shown vertically and the design repeats horizontally.

I claim:

The ornamental floral design for a flocked textile fabric, as shown and described.
